CIRCUIT BREAKER

Oliver S. Jennings and Hiller D. Dorfman, Mansfield, Ohio, assignors to Westinghouse Electric & Manufacturing Company, East Pittsburgh, Pa., a corporation of Pennsylvania

Application June 9, 1934, Serial No. 729,815

3 Claims. (Cl. 200—154)

Our invention relates to circuit interrupters and particularly to contact structures for circuit breakers such as those used with distribution feeder and moderate power network systems.

5 Circuit breakers for this type of service are subjected to very severe and exacting requirements. Operation in either direction must be reliable and positive, the breaker must carry the normal line current without undue I^2R loss, the cost of the breaker must not be excessive, and, perhaps what is most important of all, the breaker must be capable of quickly interrupting short-circuit currents of very large magnitude without damage to the structure of the breaker itself.

10 One arrangement of considerable assistance in meeting these requirements is the provision of means for causing the circuit breaker contacts to open and to close at high speeds, and the principal object of this invention is the provision of improved means for causing the arc forming contacts of a circuit interrupter to be separated (or 15 to be closed) at the maximum possible speed.

In the interests of economy, it is highly desirable that the contact structures for breakers of this type be as simple as possible. Despite this, 20 the contacts must satisfactorily carry the normal overload currents without over-heating or danger of welding. The prior art has found no better answer to the problem than a pair of solid members (preferably of an arc resisting material) 25 which engage each other with a simple butt contact. Such an arrangement permits high contact pressure with resulting high current capacity and low losses, there is little tendency for the contacts to weld together, and even if they should, the weld 30 is easily broken, and further, the contacts are very inexpensive to manufacture and simple to install.

35 Heretofore, however, no satisfactory arrangement has been known to the art for effecting the separation of butt type contacts at very high speeds, except through the provision of circuit breaker mechanisms especially designed for ultra-high-speed operation. This undesirable feature of the prior art structures has arisen more or less naturally. Butt type contacts are solid and relatively inflexible. Therefore, a spring or other resilient means must be interposed between the actuating mechanism and the contact engaged thereby 40 to assure adequate contact pressure at all times. These springs, if they are to be effective, must bias the contact member (or members) toward the closed-circuit position when the breaker is closed, and in the designs known to the prior art, the effect of the biasing springs was to cause the con-

5 tacts to remain in engagement for a very appreciable period of time after the operating mechanism had begun to move toward the open circuit position.

To overcome this undesirable characteristic, 5 complicated operating mechanisms were utilized. These mechanisms moved the movable contact member (or members) with sufficient rapidity that, despite the lag resulting from the movement of the contacts toward each other produced by the 10 biasing spring, the desired high-speed operation was effected.

15 With the structure of our invention butt type contacts are used. The contacts are resiliently biased together when the breaker is in the closed position. However, the separation of the contacts during the opening operation takes place at a speed much greater than has heretofore been considered possible in the art. In fact the contacts separate more rapidly than they would if they 20 were directly moved by the operating member itself. Our invention thus not only overcomes the disadvantages of the prior art, but provides a structure capable of operating in a manner superior even to the optimum mechanism of the 25 prior art.

25 In addition to the principal object of our invention discussed above, it is another object of our invention to provide a multi-pole circuit breaker wherein the cooperating contacts for each 30 of the several poles are caused to separate at high speed through the actuation of a single operating mechanism.

35 A further object of our invention is to provide an improved circuit interrupter which shall utilize a single movable contact member for carrying the total current normally flowing through the interrupter and for establishing the arc incident to the interruption of the controlled circuit, and which shall include means for causing the 40 contact member to be moved to the open-circuit position at high speed through the actuation of a moderate-speed operating mechanism.

An ancillary object of our invention is the provision of an improved contact structure for 45 electrical apparatus, the structural features of which in themselves accomplish the above objects of our invention.

Our invention is, as mentioned above, particularly suitable for use with circuit breakers 50 of the type normally used for distribution feeder and moderate power network systems. We shall, therefore, describe an embodiment of our invention as applied to such devices without, however, in any way tending to restrict the scope 55

of our invention except as indicated in the appended claims.

This preferred embodiment of our invention comprises generally a base of molded insulating material upon which are mounted suitable terminals for each of a plurality of poles, an operating mechanism which includes means for mechanically interconnecting the plurality of switch arms for the several poles of the breaker, and a trip device operable upon the occurrence of predetermined conditions to cause the operating mechanism to open all of the poles of the breaker. Each of the switch arms is provided with a moving contact assemblage which is actuatable during the circuit-opening operation to cause high speed separation of the engaging contacts for each of the poles. The structural features and the details of operation of this embodiment of our invention are particularly pointed out in the appended drawing and specification wherein:

Figs. 1, 2, and 3 are fragmentary views showing the position of one of the moving contact assemblages and the associated switch arm during the circuit opening operation;

Fig. 4 is an enlarged fragmentary view showing the features of our improved moving contact assemblage; and,

Fig. 5 is a sectional view taken on the line V—V of Fig. 1.

The main base 1, which is of molded insulating material, carries strips of conducting material 9 which serve to connect the terminals of the circuit breaker with their respective stationary contacts 11. The operating mechanism is supported upon the main base 1 of the circuit breaker by means of suitable screw fastenings (not shown) which engage the operating mechanism frame 17.

A movable switch member 19, which includes a movable contact assemblage 21 and a suitable supporting frame 23 therefor, is provided for each of the three poles. These three switch members 19 are mechanically interconnected by means of an insulating tie-bar 25 which extends across all three poles of the breaker. The frame 23 of the central switch member is pivotally supported on the frame 17 of the operating mechanism through a suitable pivot pin. This pivot pin provides a support for the three interconnected switch arms, and thus permits the single operating mechanism to actuate all three poles of the breaker.

Each of the switch arms 19 comprises, as mentioned above, a channel-shaped frame member 23 (Fig. 5), the side portions of which are joined at one end by a narrow strip 41 formed integral therewith and at the other end by a somewhat larger strip 43. A square-opening 45 is formed in each of the spaced side portions of the individual frame members in order to provide a space for the insulating tie-bar 25, this bar being held in position by a suitable plate 47 which is riveted to the frame itself by the rivets 49.

The movable contact assemblage 21 comprises a channel-shaped support frame 53 (Figs. 4 and 5) which is adapted to be pivotally mounted upon the frame 23 of the cooperating switch member 19 by means of a pivot pin 55 which extends through suitable aligned openings in both frames. A conducting strip 57 of somewhat greater length than the moving contact frame 53 is positioned beneath the central portion of that member, being rigidly fastened to the frame 53 adjacent its outer end by means of a rivet 59 which also serves as a support for the moving

contact member 61. The conducting strip 57 terminates in a pair of terminal portions 63 each of which is adapted to engage one of the flexible shunts 65 utilized for completing the electrical circuit from the moving contacts 61 to the other terminals of the device. A piece of spring steel 67 having a rounded end portion 69 is positioned beneath the conducting strip 57 and is securely fastened to the frame 53 of the contact assemblage by means of the rivet 71. A coil spring 73 of considerable stiffness is positioned about the pivot pin 55 and is adapted to bias the moving contact 61 toward the open circuit position at all times. The cooperating contacts 11 and 61 engage with a simple butt engagement. Each pair 15 of contacts carries the entire line current for one of the poles, and in the preferred structure the contacts are formed of arc resisting material.

The electrical circuit for each of the poles is substantially the same. Beginning with one 20 terminal the current flows successively through the conducting strip 9, the stationary contact member 11, the cooperating moving contact member 61, the conducting strip 57, the flexible shunts 65 intermediate the conducting strip 57 25 and the shunt terminal 75, and thence to the other terminal of the breaker.

A plate member 99 of insulating material of substantially the same width as the spring member 67 forming a part of each of the moving contact assemblages 21, is positioned between the opposed side portions of the frame 17, and a like plate member is similarly positioned with respect to each of the outer poles of the breaker. These insulating plates are each adapted to engage the 35 curved portion 69 of one of the springs 67 during the opening and closing movements of the breaker, so as to define the motion of the moving contacts 61. In addition, when the circuit breaker is in the closed-circuit position, these plate members 40 99 are adapted to provide a support point for the right-hand end of the moving contact assemblage which is subjected at that time to three forces. One of these forces is supplied by the operating mechanism to the switch member frame 23. 45 The second of these forces is the contact pressure force which is supplied through the butt engagement of the moving contact member 61 with the fixed contact member 11. And the third of these forces is supplied by the plate members 99 men- 50 tioned above.

The force applied to the switch member frame 23 is substantially fixed, as is the movement of that frame by the circuit-breaker operating mechanism. The action of the spring member 55 67, is to provide what is equivalent to a resilient connection between the operating mechanism and the moving contact members 61, thereby causing the cooperating contact surfaces to be held in engagement despite any inaccuracies in 60 the mechanism or any wear of the parts. In effect, when the breaker is closed, each of the movable contact assemblages 21 comprises a three-force member which is rigidly supported at one end, resiliently supported at the other 65 end, and held down by a force applied intermediate its ends. The biasing action of the springs 73 is overcome by the operating mechanism during each closing operation, and this spring is practically ineffective in reducing the 70 normal contact pressure. However, as soon as the switch member frame 23 is raised the least amount by the operating mechanism, the biasing springs 73 do become effective and, as will be pointed out later, effect the desired high speed 75

opening of the cooperating butt type contact members.

Figs. 1, 2, and 3 illustrate three instantaneous positions of one of the moving contact assemblies 21 and the associated switch member frame 23, during either the opening (or the closing) operation. Considering the opening operation, the position shown in Fig. 1 occurs a very short time after the operating mechanism begins to open the breaker. The first effect of this opening movement is to lift the moving contact assembly 21 on the switch member frame 23 a slight distance away from the base 1 of the breaker. The immediate effect of this movement is to change the moving contact assembly from a pivoted member subjected to three forces to a pivoted member subjected to only two forces. The contact assembly is thus free to rotate under the biasing action of the spring 73, and as a result, the curved portion 69 of the spring 67 is held in contact with the cooperating plate 99 affixed to the base. As the opening operation progresses, the moving contact assembly 21 is progressively moved through the positions shown in Figs. 2 and 3, to its fully open position where the contacts 11 and 61 have approximately twice the separation shown in Fig. 3.

It is immediately apparent that the result of this is to cause a much more rapid separation of the cooperating contact surfaces than would result if the contact members 61 were moved directly by the switch member frames 23. It is also apparent that by properly proportioning the dimensions of the moving contact structure, the speed of separation of the contacts can be varied over a wide range.

This arrangement, which permits the opening of the moving contacts to be effected at high speed, is one of the principal features of our invention, and in connection therewith, it is important to note that when the contacts are in the fully open position the amount of contact separation is greater than could be effected if the moving contacts 61 were rigidly supported on the switch member frame 23, or if it were supported by the usual contact pressure-securing spring. As contrasted with the usual form of contact assembly, our moving contact members are biased not to the closed-circuit position but to the open-circuit position, except when the breaker is in the fully-closed position. At that time a second spring is stressed to provide the desired contact pressure and to provide a resilient connection intermediate the operating mechanism and the contact members themselves.

It should also be noted that if the center of gravity of the movable contact assembly 21 is to the right of the pin 55, the resulting inertia effect will, during the opening and the closing of the breaker, produce substantially the same effect as the spring 73. With such an arrangement the spring 73 can be made comparatively weak, since its chief function will be the holding of the contact arm in the extreme open-circuit position when the breaker is in the open-circuit position.

Through the provision of means whereby the moving contacts are caused to disengage the cooperating stationary contacts at very high speed, which means at the same time produces a greater separation of the cooperating contacts than would be possible if the moving contact were rigidly fixed to the associated switch member frame, it is possible to use a much less expensive mechanism for actuating the circuit breaker. This results from

the fact that a moderate speed mechanism can be utilized for securing high-speed opening of the circuit breaker contacts, and also from the fact that a much greater separation of the contacts than has heretofore been considered possible for an operating mechanism of given dimensions is made possible. To summarize, not only does our invention permit the use of a less expensive, slower speed mechanism, but in addition it permits the use of one having smaller physical dimensions than has heretofore been considered possible.

From the foregoing it will be seen that we have provided an improved circuit breaker contact structure which possesses numerous advantages over, and which differ very materially from the structures heretofore known in the art. We have provided a moving contact assembly which utilizes butt type contacts and which is capable of opening those contacts at much higher speeds than has heretofore been believed possible, except through the provision of special ultra-high speed operating mechanisms; this improved operation of the structure of our invention being effected, in part, through the agency of means for normally biasing the contacts to the open position, as against the usual arrangement for biasing the contacts to the closed position, in combination with an auxiliary means for securing the desired contact pressure when the circuit breaker contacts are in the closed-circuit position, thus permitting the use of the highly desirable type of butt contacts.

Moreover, our improved form of contact structure not only secures a higher speed opening of the cooperating contacts than has heretofore been possible, but in addition it effects a much greater separation of those contacts for a definite movement of the actuating mechanism than has been known to the prior art.

While in accordance with the patent statutes we have disclosed the foregoing details of a specific embodiment of our invention, and while certain of the claims are directed to the details of this preferred embodiment, it is to be understood that the principles disclosed are capable of much wider adaptation to the art of circuit interruption generally. We desire, therefore, that the language of our claims shall be accorded the broadest reasonable construction, and that our invention shall be limited only by what is expressly stated therein and by the prior art.

We claim as our invention:

1. In a circuit interrupter; a base member; a stationary contact means; a switch arm movable to an open and to a closed circuit position; a contact assembly pivotally mounted on said switch arm; and actuating means for moving said switch arm to open and to close said interrupter; said contact assembly including a contact member which is adapted to engage said stationary contact means and which is positioned at one side of the pivot point of said assembly, a tail portion which is mechanically connected at one end thereof to said contact member and which has a portion positioned at the other side of the pivot point of said assembly, and spring means which biases said assembly for rotation about the said pivot point toward the open circuit position; the end of said tail portion opposite to that which is connected to said contact member being held in slidably engagement with said base member by the reaction force of said biasing means at all times during the operation of said switch, in order that said contact assembly shall be caused to

rotate about its axis during the circuit opening operation, in such manner that said contact member shall be moved away from said stationary contact means, during the entire opening operation of said switch, at a rate of motion greater than the rate which would result if said contact member were rigidly connected to said switch arm.

2. In a circuit interrupter; a base member; a stationary contact member fixedly supported thereon; a pivotally mounted switch arm movable to an open and to a closed circuit position; a contact assemblage; means for pivotally supporting said contact assemblage on said switch arm, adjacent the unpivoted end thereof; and actuating means for rotating said switch arm about its pivot point to open and to close said interrupter; said contact assemblage including a frame which is engaged by said means for pivotally supporting said assemblage intermediate the ends thereof, a movable contact member affixed to the outer end of said frame for cooperating with said stationary contact member, spring means biasing said frame for rotation in such direction that said movable contact member is biased away from said stationary contact member, and a tail portion which is affixed at one of its ends to said frame and which has a portion positioned at the inner side of the pivot point of said frame, that portion extending along said switch arm a substantial distance; the end of said tail portion opposite to that which is affixed to said frame slidably engaging said base member in order to control the movement of said frame and said movable contact member under the action of said biasing means during the operation of said interrupter; the dimensions of said tail portion and said frame and the positioning of the several pivot and engagement points being so correlated that said movable contact member is caused to disengage said stationary contact member, during the entire circuit opening operation, at a rate of motion substantially greater than the rate of motion which would result if said contact means were rigidly connected to said switch arm.

3. In a circuit interrupter; a base member; a rigid, non-resilient stationary contact member fixedly supported thereon; a pivotally mounted

switch arm which is movable to an open and to a closed circuit position and which comprises a substantially U-shaped frame; a contact assemblage; means including a pin for pivotally supporting said contact assemblage on said U-shaped switch arm, adjacent the unpivoted end thereof; and actuating means for rotating said switch arm about its pivot point to open and to close the interrupter; said contact assemblage including a U-shaped auxiliary frame, the side portions of which are engaged by said support pin intermediate the ends of said auxiliary frame, a substantially rigid contact member affixed to the outer end of said auxiliary frame for cooperating with said rigid stationary contact member, spring means biasing said auxiliary frame for rotation about said pin in such direction that said movable contact is biased away from said stationary contact member, and a resilient tail portion which is affixed at one of its ends to said auxiliary frame and which has a portion positioned at the inner side of the pivot point of said auxiliary frame, that portion extending along said switch arm for a substantial distance; the end of said tail portion opposite to that which is affixed to said auxiliary frame slidably engaging said base member in order to control the movement of said auxiliary frame and said movable contact member supported thereon under the action of said biasing means during the operation of said interrupter; the dimensions of said tail portion and said auxiliary frame and the positioning of the several pivot and engagement points being so correlated that said movable contact member moves away from said stationary contact member, during the entire circuit opening operation, at a rate of motion substantially greater than the rate of motion which would result if said movable contact member were rigidly connected to said U-shaped switch arm, and said tail portion being formed of resilient material in order that said rigid contact members may be resiliently biased into engagement with each other when said interrupter is in the closed circuit position.
